UNITED STATES PATENT OFFICE.

ANKER S. LYHNE, OF BRIDGEPORT, CONNECTICUT.

CASE FOR POCKET FLASH-LIGHTS.

1,160,519.

Specification of Letters Patent. Patented Nov. 16, 1915.

Application filed January 21, 1915. Serial No. 3,617.

To all whom it may concern:

Be it known that I, ANKER S. LYHNE, a citizen of the United States, residing at Bridgeport, county of Fairfield, State of Connecticut, have invented an Improvement 5 in Cases for Pocket Flash-Lights, of which the following is a specification.

This invention has for its object to provide a strong, durable and inexpensive slip-joint case for pocket flashlights, the parts of which may be readily drawn and formed from blanks of sheet metal and which will be flat, smooth and round-cornered, that is without corners or angular projections of 15 any kind, so that it will be pleasant to hold in the hand and not destructive to pockets when carried therein.

With these and other objects in view I have devised the novel flashlight case which 20 I will now describe, referring to the accompanying drawing forming a part of this specification and using reference characters to indicate the several parts:—

Figure 1 is an elevation of my novel flashlight case, as in use; Fig. 2 a longitudinal section of the case showing a lamp and battery in place; Fig. 3 a detail sectional view on an enlarged scale illustrating steps in the process of manufacture; Fig. 4 a similar view showing the manner in which the lamp holder is locked in place, and Fig. 5 is a perspective view, partly broken away, of the body member of the case detached.

10 denotes the body member, 11 the cover member, 12 the lamp holder, 13 a lamp, and 14 an ordinary commercial dry cell battery.

The body member, cover member and the lamp holder are drawn and formed from blanks of sheet metal. The body member is 40 integral and its open end is reduced in diameter outward from a shoulder 15, the shoulder and reduced end being formed by die-work and the member being formed complete from the blank. This reduced end is 45 adapted to pass into the open end of the cover member, the edge of which abuts against the shoulder, as shown in Figs. 1 and 2, so that when the members are placed in engagement the outside of the case is 50 perfectly smooth, there being simply a line at the intersection of the edge of the cover member with the shoulder of the body member, as in ordinary slip cover boxes. So far as I am aware, however, no box or case of 55 this type has ever been made in this manner, that is, with the body member formed

in a single piece and the end that receives the cover member reduced by die-work. At the closed end of the body member I form a hole to receive the lamp holder. Surrounding this hole is a flange 16 and surrounding the flange a raised rib 17. The lamp holder is provided with a recess 32 to receive a lamp in the usual manner and with the usual rolled thread 18 which is engaged 65 by the thread upon the base of the lamp. Surrounding the lamp recess in the holder is an outwardly extending flange 19 which in the assembled position, as in Fig. 3, is adapted to rest upon flange 16 of the body 70 member. The lamp holder is locked to the body member by a blow of a punch suitably shaped to close the metal of the rib over inward and downward upon flange 19 so that said flange is firmly gripped between the 75 folded rib, indicated by 20 in Fig. 4, and flange 16.

21 and 22 denote the contacts of the battery, one of which is adapted in use to permanently engage the center contact 23 of the 80 lamp, the other being adapted to be engaged by a sliding contact 24 to close the circuit. The sliding contact is operated by means of a stud 25 which passes through a slot 26 in the body member and is provided with an 85 external head 27. The sliding contact is provided near its other end with a slot 28 through which a stud 29 seated in the cover member projects. This stud serves as a 90 guide for the sliding contact and the outer end thereof comprises a boss 30 which cooperates with a depression 31 in the inner side of the cover member to lock the two members together under the ordinary conditions of use, that is, so that the members will 95 not become separated in carrying or handling but permitting the cover member to be removed by a slight pull when it is necessary to renew the battery.

Having thus described my invention I 100 claim:—

1. A slip-joint case of the character described comprising a cover member having an internal depression, an integral body member having a shoulder and its open end 105 reduced in diameter from the shoulder outward to enter the cover member, a lamp holder secured at the closed end of the body member, a sliding contact having a slot and a guide stud passing through the slot, the 110 outer end of said stud forming a boss adapted to engage the depression in the cover

member to retain said members in engagement.

2. A slip-joint case of the character described comprising a cover member having an internal depression, an integral body member having a shoulder and its open end reduced in diameter from the shoulder outward to enter the cover member, a lamp holder secured at the closed end of the body member, a sliding contact on the body mem-

ber, and means for engaging the depression in the cover member to retain said members in engagement.

In testimony whereof I affix my signature in presence of two witnesses.

ANKER S. LYHNE.
